Patented Apr. 26, 1921.

UNITED STATES PATENT OFFICE.

WILLIAM A. EDWARDS, OF CHICAGO, ILLINOIS, ASSIGNOR, BY MESNE ASSIGNMENTS,
TO WILLIAM REID, OF CHICAGO, ILLINOIS.

CARBURETER.

1,375,684.

Specification of Letters Patent. Patented Apr. 26, 1921.

Application filed November 15, 1915, Serial No. 61,505. Renewed February 3, 1921. Serial No. 442,543.

To all whom it may concern:

Be it known that I, WILLIAM A. EDWARDS, a citizen of the United States, residing at Chicago, in the county of Cook and State 5 of Illinois, have invented certain new and useful Improvements in Carbureters, of which the following is a specification.

This invention pertains in general to carbureters for use with gas engines, and more 10 particularly to the type in which the fuel supply, or as it is commonly called the needle, valve is automatically controlled by movements of the auxiliary air supply valve.

In my co-pending application, Serial No. 15 49,207, filed September 7, 1915, I have disclosed a carbureter in which the needle valve is controlled directly from the auxiliary air supply valve, so that the needle valve is opened proportionately to the opening of 20 the auxiliary air valve. It has been found, however, that in certain types of engines, particularly those employing eight or more cylinders, it is essential that a very rich mixture be supplied during the starting or 25 acceleration period of the engine. To meet this condition my present invention is designed primarily to furnish to the vaporizing chamber an unusual amount of gasolene during the period of acceleration of the engine, and to subsequently supply gasolene 30 in direct proportion to the amount of air taken in so that a mixture of uniform and predetermined richness will be maintained.

Another object of my invention is to provide 35 mechanism which will perform the functions and fulfil the requirements above mentioned entirely automatically, so that no manual adjustments of the carbureter need be made by the driver when the engine is to 40 be started, thereby obviating any possibility of delivering to the cylinders an improper or inefficient mixture. Furthermore, by making the operation of the carbureter and the proportioning of the liquid fuel to the 45 air entirely automatic the highest engine efficiency under all conditions of use is secured.

In order to facilitate an understanding 50 of my invention I have illustrated on the accompanying drawings one preferred embodiment thereof from an inspection of which, when considered in connection with the following description, the principles of the invention and many of its inherent and

attendant advantages will be readily appreciated. Referring to the drawings—

Figure 1 is a central vertical sectional view of a carbureter embodying my invention, the float chamber appearing in side elevation;

Fig. 2 is a sectional view taken on the line 2—2 of Fig. 1; and

Fig. 3 is a fragmentary sectional view showing certain of the parts in the position which they will assume when the engine is 65 being started.

Referring to the drawings, the casing of the carbureter is of skeleton construction comprising a vertical tube 5, the upper portion of which forms the mixing or vaporizing 70 chamber 6 and is provided with a flange 7 for connection to the intake or manifold of the engine, an auxiliary supply chamber or passage 8 communicating laterally with the mixing chamber, a constant air supply conduit 9 communicating with the lower end of the tube 5, a dash pot cylinder 10 below the juncture of the tubes 5 and 9, a piston rod housing 11 extending from the dash pot cylinder 10 obliquely across the air supply pipe 75 9 and into the auxiliary air chamber 8, and the well or housing 12 forming a continuation of the dash pot cylinder 10 in which the fuel valve is mounted, as will be later described. A float chamber 13 of any well known or preferred construction is positioned at one side of the housing 12, the bottom of the chamber being in communication with the central chamber 15 of the housing 12 and with the dash pot cylinder 90 10 through a conduit or duct 14, preferably of Venturi shape. The float chamber is also in communication with the upper end of the dash pot chamber through one or more ducts or tubes 16, which permits a free flow 95 of liquid back and forth between the float chamber and the dash pot cylinder as the dash pot piston reciprocates therein, as will be later described.

A Venturi tube 17 is mounted in the lower 100 end of the tube 5 and a nozzle piece 18 of the fuel or needle valve projects upwardly into the lower end of this tube, the nozzle piece being threaded through the housing 12 as clearly shown in Fig. 1. Slidably mounted within the nozzle piece 18 is the metering pin or needle 19 which has a hollow externally threaded stem 20 slidably but non-ro-

tatably connected at its lower end with a guide or controlling member 21 by means of a pin and slot connection comprising a pin 22 extending transversely of the member 21 and oppositely disposed slots 23 formed in the member 20 and into which the pin 22 projects. The member 21 extends through the lower wall of the housing 12 and has a bearing against the outer end of a tubular member 24 which is equipped with a suitable packing gland 25 to prevent leakage around the member. The projecting end of the member 21 is equipped with a cross pin 26 or some suitable finger hold by which it may be turned for purposes of adjustment. A coiled expansion spring 27 interposed between the upper end of the member 21 and the upper end of the bore in the stem 20 urges the needle or metering pin toward its seat, the closing movement of the metering pin being limited by an annular collar 28 threaded upon the stem 20 and adapted to abut against the lower end of the nozzle piece 18, as shown in Fig. 1. It will be obvious that the normal position of the metering pin can be regulated to a fine degree of nicety by turning the member 21, which turns the metering pin within the collar 28, which is held against rotation with the stem 20 by a pivoted lever 29, the structure and purpose of which will be later described. The upper end of the mixing chamber 6 is equipped with the usual throttle valve 31 and the air intake pipe 9 is equipped with the usual butterfly valve 32. The auxiliary air supply chamber 8 is controlled by an air intake valve 33 of relatively large area normally seated against a valve seat or ring 34 by a coiled expansion spring 35 interposed between the lower end of the valve hub or stem 36, which is threaded upon the upper end of a piston rod 37, and the bottom of a sleeve 38 disposed within the piston rod housing 11 around the stem or hub 36. The tension of the spring 35 may be regulated by adjusting the sleeve 38 longitudinally in its housing, this result being accomplished by means of a lever 39 attached at one end to the sleeve 38 and fixed at its other end in a rock shaft 41 which is equipped with an operating lever 40, which may be manipulated or adjusted by any suitable mechanism under the control of the driver. The lower end of the piston rod or stem 37 is enlarged as indicated at 42 to provide a firm sliding bearing in the housing 11 and carries at its lower end within the piston chamber 10 a piston or plunger, designated generally by reference character 43, which is attached to the piston stem by an internal nut 44. The piston 43 fits snugly but slidably within the piston chamber 10, and it will be manifest that when the auxiliary air valve 33 is opened against the force of the spring 35 by 65 an inflow of air through the chamber 8 the

piston 43 will be forced downwardly in the piston chamber the same distance that the valve 33 is moved inwardly from its seat.

In my co-pending application, hereinbefore mentioned, a direct connection was made between the piston 43 and the needle valve so that as the piston was forced downwardly the needle valve would be correspondingly moved away from its seat to increase the supply of liquid fuel to the vaporizing chamber. In the present instance I have provided a construction by which the initial downward movement of the piston 43 is multiplied and transmitted to the needle valve with the result that the needle valve is withdrawn from its seat a distance greater than the movement of the piston to thereby supply an initial charge of fuel of relatively large volume. After this initial charge has been delivered and the engine has passed its period of acceleration or, in other words, has "picked up," the needle valve is permitted to move back a limited distance toward its seat and is then maintained under the direct control of the piston 43 to be moved toward and from its seat proportionately to the movements of the piston and in accordance with variations in the speed of the engine.

With this end in view the piston 43 is equipped with a downwardly projecting annular flange 45 forming an annular chamber within the body of the piston itself in which a supplemental piston 46, snugly but slidably fitting the inner faces of the flange 45, is positioned. This supplemental piston is provided with a stem 47 projecting upwardly into the stem 37 of the main piston, and an expansion spring 48 interposed between the bottom of a bore 49 in the enlarged portion 42 of the main piston stem, and a shoulder formed on the stem 47 normally urges the piston 46 into its lowermost position, as shown in Fig. 1. Downward movement of the piston 46 is limited by a flange 51 formed on a pivot pin 52 which is threaded into the piston 43 just outside the flange 45. The lever 29, which has been previously mentioned, is pivoted intermediate its ends upon the pin 52 between two transversely extending pins 53 and 54 respectively, the lever being provided with an elongated aperture 55 through which the pin 52 projects and which permits limited longitudinal movement of the lever 29 upon its fulcrum sufficient to prevent binding of the lever in operation. One end of the lever 29 is connected to a stud 56 projecting downwardly from the piston 46 by means of a transverse pin 57, and the other end is bifurcated as shown in Fig. 2 to embrace the collar 28 which is threaded upon the stem 20. It will be observed that the collar 28 is provided with a circumferential groove in which the bifurcated ends of the lever 29 are 130

disposed, and that this groove is divided by one or more vertically disposed webs 58, one of which engages in a similarly shaped notch 59 formed in the lever 29 and by 5 which the collar 28 is prevented from rotating when the stem 20 of the needle valve is turned for purposes of adjustment. To prevent the formation of a vacuum behind the piston 46 a port 61 is provided in the main 10 piston 43 through which communication is established between the supplemental chamber and the chamber above the main piston. It should be noted that the circumferential groove in the collar 28 is a little wider than 15 the thickness of the lever 29 so that a limited amount of lost motion is provided in the connection between the auxiliary air valve and the needle of the fuel valve, which during normal running of the engine affords a 20 delayed action of the air valve on the fuel valve which renders the carbureter extremely sensitive and responsive in operation.

The operation of my invention is substantially as follows: Assuming that the engine 25 to which the carbureter is attached is standing idle, the piston chamber and the central chamber 15 and a portion of the nozzle member 18 will be filled with gasoline. The engine is now turned over or started, by hand 30 or by power, as the case may be, and the suction of the cylinders will cause the auxiliary air valve 33 to move inwardly away from its seat in the usual manner. The initial downward movement of the piston 43 by the auxiliary air valve 33 will, of course, positively 35 force a quantity of fuel upwardly through the needle valve. The formation of any vacuum above the piston 43 is prevented by the ducts or tubes 16 connected directly with 40 the float chamber which permit gasoline to flow from the float chamber into the space above the piston as the piston moves downwardly. If the needle valve were connected 45 directly with the piston 43 the needle would be moved downwardly proportionately to the downward movement of the piston. As previously stated, however, it is essential to engines of eight or more cylinders that an 50 unusually rich mixture be delivered during the period of acceleration. This result is accomplished in my present invention by the supplemental piston 46 which as the piston 43 moves downwardly against the pressure 55 of the fluid in the chamber 10, will be moved upwardly relatively to the piston 43 against the force of the spring 48. As the pivot pin 52 travels downwardly with the piston 43 and as the piston 46 moves upwardly relatively 60 to this pin it will be manifest that the lever 29 will be rocked about its fulcrum into the position shown in Fig. 3, thereby withdrawing the metering pin 19 from its seat a suitable distance to permit an unusually 65 large flow of fuel through the needle valve

into the mixing chamber. This maximum flow of liquid which produces an extremely rich mixture is, however, only temporary, for the reason that as soon as the pressure of the fuel in the piston chamber 10 below 70 the pistons has been reduced by the discharge of the liquid through the needle valve the piston 46 will be returned to its normal position by the spring 48, which return movement will partially close the needle 75 valve and correspondingly restrict the flow of fuel. This unusually large although temporary flow of fuel permitted by the construction just described is sufficient to take care of the period of acceleration of the 80 engine, and thereafter the flow of fuel should be proportionate to the flow of air through the carburetor which is, of course, controlled by the speed of the engine. After the piston 46 has resumed its normal position 85 relatively to the piston 43 so long as the engine continues to run and relieve the pressure in the piston chamber below the pistons the main and supplemental pistons 43 and 46 respectively, will move back and 90 forth under the control of the air valve 33 as a unit, and the needle valve will be opened and closed in proportion to the opening and closing of the air valve. The width of the groove around the collar 28 will, however, 95 permit a slightly delayed action of the needle valve which is conducive to the highest engine efficiency. When the engine is stopped the fuel pressure in the piston chamber will again be restored and the operation 100 of the carburetor when the engine is next started will be similar to that just described. It will be obvious that the formation of a partial vacuum above the supplemental piston 46 which would interfere with the sensitivity of the device is obviated by the port 105 61 which permits a free ingress and egress of liquid as the piston reciprocates in its chamber.

It is believed that the principles of my invention, its mode of operation and structural details of one embodiment thereof will be fully understood from the foregoing without further description, but it should be manifest that the principles of my invention are capable of embodiment in construction differing materially from the structural details herein illustrated and described.

I claim:

1. In a carbureter, the combination of an air valve, a fuel valve, and connections between said valves whereby said fuel valve is controlled by movements of the air valve, said connections including means for producing a maximum movement of said fuel valve relatively to the air valve upon initial opening of said air valve and thereafter a like movement of the fuel valve and the air valve.
2. In a carbureter, the combination of a

- fuel valve, an air valve, and operative connections between said valves including a fulcrum movable with said air valve and a lever attached at one end to said fuel valve and yieldably connected at its other end to said air valve whereby said fuel valve is controlled by the air valve.
3. In a carbureter, the combination of a fuel valve, an air valve, a piston connected to said air valve, a fulcrum pin carried by said piston, a lever fulcrumed on said pin and connected at one end to said fuel valve, and a supplemental piston attached to the other end of said lever.
- 10 4. In a carbureter, the combination of a fuel valve, an air valve, a main piston connected to said air valve, a supplemental piston carried by said main piston and movable relatively thereto, a fulcrum fixedly attached to said main piston, and a lever pivoted on said fulcrum and connected at one end to said fuel valve and at its other end to said supplemental piston.
5. In a carbureter, the combination of a fuel valve including a metering pin, a spring for yieldably urging said pin toward its seat and a collar adjustably mounted on said pin, an auxiliary air valve, a dash pot piston connected therewith, a supplemental piston carried by said dash pot piston, and a lever carried by said dash pot piston and connected to said supplemental piston and to said collar.
- 25 6. In a carbureter, the combination of a fuel valve, an auxiliary air intake valve, a dash pot piston connected with said air intake valve and constructed to provide a supplemental piston chamber, a supplemental piston disposed in said chamber, a fulcrum pin mounted on said dash pot piston, and a lever fulcrumed on said pin, said lever being pivotally connected to said supplemental piston and adjustably connected to said fuel valve.
- 15 7. In a carbureter, the combination of a dash pot chamber, a float chamber connected therewith, a fuel nozzle in communication with said dash-pot chamber, a fuel valve controlling said fuel nozzle, an air intake valve, a main piston mounted in said dash pot chamber, an operative connection between said piston and said fuel valve, and means for establishing connection between said float chamber and said dash pot chamber both below and above said piston.
- 20 8. In a carbureter, the combination of a float chamber, a dash pot chamber connected therewith, a main piston in said dash pot chamber, an air valve connected to said piston, a supplemental piston yieldably mounted on said main piston, a fuel valve, operative connections between said fuel valve and said supplemental piston, and a conduit establishing communication between said float chamber and said dash pot chamber above the main piston, said main piston being constructed to provide communication between the supplemental piston chamber and said dash pot chamber above the main piston.

WILLIAM A. EDWARDS.
